US0D1002343S

(12) **United States Design Patent** (10) **Patent No.:** **US D1,002,343 S**
(45) **Date of Patent:** **** Oct. 24, 2023**

(54) **CASE FOR ELECTRONIC DEVICE**

(71) Applicant: **Catalyst Lifestyle Limited**, North Point (HK)

(72) Inventors: **Joshua Wright**, Hong Kong (CN); **June Lai**, Hong Kong (CN)

(73) Assignee: **CATALYST LIFESTYLE LIMITED**, North Point (HK)

(**) Term: **15 Years**

(21) Appl. No.: **29/884,831**

(22) Filed: **Feb. 16, 2023**

Related U.S. Application Data

(62) Division of application No. 29/726,011, filed on Feb. 28, 2020, now Pat. No. Des. 986,713.

(51) **LOC (14) Cl.** **09-06**

(52) **U.S. Cl.**

USPC **D8/356**; D3/294

(58) **Field of Classification Search**

USPC D14/440, 447; D3/294, 301, 218

CPC H04R 1/028; G06F 1/1628; G06F 1/1626;

A47B 23/044; A45C 11/00; H04B 1/3888

See application file for complete search history.

(57) **CLAIM**

The ornamental design for a case for electronic device, as shown and described.

DESCRIPTION

FIG. 1 is a perspective view including the rear, top, and side of a case for electronic device in a closed condition showing our new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a bottom plan view thereof;

FIG. 7 is a top plan view thereof;

FIG. 8 is a perspective view thereof including the front, top, and side in an open condition;

FIG. 9 is a front elevation view of FIG. 8;

FIG. 10 is a rear elevation view of FIG. 8;

FIG. 11 is a side elevation view of FIG. 8;

FIG. 12 is an opposite side elevation view of FIG. 8;

FIG. 13 is a top plan view of FIG. 8; and,

FIG. 14 is a bottom plan view of FIG. 8.

The broken lines shown in the drawings depict portions of the case for electronic device that form no part of the claimed design.

1 Claim, 14 Drawing Sheets
